(57) **CLAIM**

The ornamental design for a spray mop, as shown and described.

DESCRIPTION

FIG. 1 is a perspective view of a spray mop showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is a partially enlarged view showing the area "9" in FIG. 2.

The even broken lines shown in the drawings illustrate portions of the spray mop that form no part of the claimed design. The dot-dash broken lines indicating an enlargement portion of the design form no part of the claimed design.
